(57) CLAIM

The ornamental design for a heart shaped candy display stand with a bite taken out of it, as shown and described.

DESCRIPTION

FIG. 1 is a perspective view of a heart shaped candy display stand with a bite taken out of it showing my new design; and, FIG. 2 is a front elevation view thereof.

The broken lines are shown for the purpose of illustrating portions of the heart shaped candy display stand with a bite taken out of it that form no part of the claimed design.
